UNITED STATES PATENT OFFICE

2,536,277

FLAT LEAKPROOF OILER

Walter Grieme, Osawatomie, Kans.

Application June 20, 1947, Serial No. 756,065

2 Claims. (Cl. 222—385)

1

This invention relates to improvements in lubricating apparatus, and more particularly to a hand pump operated oiler.

An object of the invention is to provide a flat, non-leaking oiler having a pump and a swinging spout that seals itself when the spout is in non-oiling position.

Another object of the invention is to provide an oiler which is conveniently carried in a tool box, a garment pocket or tool bag, that is leak-proof, handy and easy to use, provided with a spout that can be swung to either the sides or front thereof, and will house the spout in non-oiling position so that the spout will not protrude beyond the oiler in a dangerous position when not in use.

With the above and other objects and advantages in view, the invention consists of the novel details of construction, arrangement and combination of parts more fully hereinafter described, claimed and illustrated in the accompanying drawings in which:

Figure 1 is an elevational view of an embodiment of the invention, partly broken away, to show the pumping mechanism thereof;

Figure 2 is an elevational view showing the spout in oiling position and partly broken away to show filler opening and plug;

Figure 3 is a top plan view of Figure 2;

Figure 4 is a sectional view on the line 4—4 of Figure 1;

Figure 5 is a fragmentary detailed view of the pumping mechanism and spout in non-oiling position;

Figure 6 is the same, with the pump and spout in oiling position;

Figure 7 is a sectional view on the line 7—7 of Figure 5 with the spout in closed position;

Figure 8 is the same, with the spout in oiling position toward the front of the oiler;

Figure 9 is the same as Figure 7, with the spout in oiling position toward the side of the oiler and

Figure 10 is the same, with the valve in bleeding position to permit oil in the pump to return to the reservoir.

Referring more in detail to the drawings, the reference numeral 20 designates the oiler embodying the invention, which comprises the reservoir or body 21 which is comparatively flat and rectangular in shape. Mounted within the body 21, which is hollow to contain oil or other fluids therein, is the U-shaped support 22 having a base 23 of the same width as the body 21 and which, on the bottom thereof, and the uprights

2

24 of the support 22, are of the same width as the base 23, and engage the inner surface of the ends and sides of the body 21.

The top 25 rests on the upper ends of the uprights 24, and is inset with regard to the upper edge of the body 21 to form a smooth top surface thereon. Centrally thereof the top is provided with a screw type filling plug 26 which is also inset with regard to the top surface of the oiler, and the plug is used to fill the body with oil or other fluids.

Secured to the base 23 of the support 22, in vertical relation thereto is the pump cylinder 26 in which is mounted the piston 27, the stem 28 of which extends upwardly through the opening 29 in the top 25. A rubber sealing gasket 30 mounted in the openings about the stem produces a fluid leakproof seal to prevent the oil from leaking out of the body about the stem 28, and a washer 31 aids in retaining the gasket in the body. An expansion spring 32 on the stem 28 engaging the top of the cylinder 26 and a disc collar 33 on the stem forces the piston upwardly, and the stem outwardly of the body 25 as shown in Figure 6. A knob 34 on the upper end of the stem provides a contact means for reciprocating the piston 27 to pump oil from the cylinder 26 which enters therein by means of the upper and lower rows of perforations 35 and 35' respectively, and is discharged therefrom by the conduit 36 communicating with the cylinder 26 adjacent the bottom thereof.

The conduit 36, at its opposite end communicates with the valve casing 37, in which is mounted the 180 degree valve 38 having the curved outlet 39 communicating with the pouring or oiling spout 40.

Communicating with the outlet 39, by means of the groove 39', which extends about the valve body 37 at the center thereof in a 180 degree arc, are the ports 41, 42 and 43 respectively, which permit the spout to close all ports, and the groove 39' when in closed position, as in Figure 7, to oil to one side when port 43 is in communication with conduit 36 by the groove 39' as in Figure 9, or to oil to the other side when port 41 is in communication by the groove 39' with conduit 36. When port 42 communicates with conduit 36, the spout will oil to the front, and when conduit 36 is in communication with the perpendicular bleed vents 44 or 44' in the valve, the oil in the pump will be returned to the reservoir. This occurs by reason of the fact that vents 44 and 44' have no connection with the groove 39' but just before the spout is returned

to closed position, the conduit 36 alining with these vents discharges the oil from the conduit so that the oil will not be discharged from the spout when in closed position. While the aforementioned positions are positive positions, the groove 39' permits the spout to oil at any position through a 180 degrees arc. A threaded lug 38' on the bottom of valve 38 on which the nut 39' is threaded engages the spring washer 40' and retains the valve 38 in the casing 37 by 10 contacting the lower edge of the casing 37 outwardly of the valve 38.

Hinged at 45 on the top 25 is a pressure bar 46 which extends forwardly of its hinged end to be engaged under the protruding lug 47 formed on the valve 38 below the spout 40. Thus the pressure bar 46 which engages the knob or contacting means 34 will hold the piston 27 in inoperative position as shown in Figure 5. When the spout is in closed position, as shown in Figure 1, in which it will also be seen that a plate 48, hinged at 49, can be swung into position so that a cap 50 formed thereon will engage the open end of the spout to retain it in position within the confines of the body 21 to prevent the spout from sticking outwardly thereof. To further protect the parts mounted on the top 25, a removable cover 51 is positioned on the upper edge of the body 21 and retained therein by means of spring latches 52 on the cover 51 engaging the detents or keepers 53, formed on the ends of the body 21.

In operation, the cover 51 is removed, and the spout is swung to the position shown in Figure 8 and Figure 9, or the reverse of Figure 9, to disperse oil or other fluid from the oiler. Movement of the spout will disengage the lug 47 from the free end of the bar 46, to permit the spring 32 to force the piston and bar upwardly to the position shown in Figure 2. Pressure on the bar 46 will reciprocate the piston 27 to pump oil or other fluids out of the spout 40 as desired. When the lubricating operation is completed, the spout is turned into the position shown in Figure 1, the lug is engaged with the bar 46 and the end of the spout is engaged in the cup 50. The cover is then replaced, and a leakproof safety oiler is provided.

There has thus been provided an oiler which,

it is believed, will accomplish the objects of the invention, and it is believed that the structure and operation thereof will be apparent to those skilled in the art. It is also to be understood that changes in the minor details of construction, arrangement and combination of parts may be resorted to, provided they fall within the spirit of the invention, and the scope of the appended claims.

Having thus described the invention, what is claimed as new and desired to be secured by Letters Patent is:

1. A lubricating apparatus of the character described, comprising a hollow body, a pump in said body adjacent the bottom thereof, said pump comprising a cylinder, a piston mounted therein, a stem on said piston extending outwardly of said body, a valve casing in said body, a three way valve in said casing, a conduit forming communication between said cylinder and said valve casing to discharge oil from said cylinder to said casing, means in said cylinder to permit oil to enter therein, means for forcing said piston outwardly of said cylinder, means for engaging said stem for the reciprocation thereof to force fluid outwardly of said cylinder through said spout, and means on said valve for engaging the means for reciprocating said piston to retain said piston in inoperative position.

2. The invention as in claim 1, wherein means is provided on the means for reciprocating said piston for closing the open end of said spout to prevent leakage therefrom.

WALTER GRIEME.
